STARTER FOR INTERNAL-COMBUSTION ENGINES

Harry da Costa, London, England, assignor to The Plessey Company Limited, Ilford, England, a British company

Application April 3, 1942, Serial No. 437,539
In Great Britain March 19, 1941

11 Claims. (Cl. 123—179)

This invention relates to starters for internal-combustion engines and is concerned with starters especially for large or heavy engines and in particular aircraft engines.

According to the invention there is provided a starting apparatus for internal-combustion engines comprising an auxiliary internal-combustion engine for turning the engine to be started through a reduction gear train and a cartridge operated device for starting the auxiliary engine.

According to a further feature of the invention there is provided means automatically operated by the initial rotation of the auxiliary engine for coupling the auxiliary engine directly to the engine to be started. Alternatively, the auxiliary engine may be coupled to the engine to be started by means of a hydraulic or centrifugal clutch.

Another feature of the invention consists in that the engine to be started is initially turned through the reduction gearing by the cartridge operated device in starting the auxiliary engine.

Yet another feature of the invention consists in the provision of means automatically operated by the auxiliary engine for varying the fuel supply to this engine during the running period. Thus, it may be necessary gradually to weaken the fuel and air mixture applied to the auxiliary engine and there may be provided a fuel control valve, for example, an air strangler valve actuated by a pressure operated device which is in turn operated by a fluid pressure which is caused to be built up by the rotation of the auxiliary engine over a period. The pressure operated device may act on the valve against the action of a return spring.

Another feature of the invention consists in means for putting the starter into operation which comprises a cartridge firing control member which is also coupled to means for placing the auxiliary engine in running condition so that it is only necessary to operate this control member to set the starting apparatus fully into operation. For instance, the control member may be arranged to switch on the ignition and fuel supply to the auxiliary engine when it is operated to fire a cartridge.

The torque which is necessary to turn the engine to be started varies considerably with temperature conditions and it is preferable to provide a change-speed gear which may be of simple form in the drive between the auxiliary engine and the engine to be started.

It is a further feature of the invention to construct the auxiliary engine, the reduction gear train and the cartridge operated device in a small compact unit for mounting close to the engine to be started. The cartridge chamber may be remote from this unit and connected

thereto by a pipe for carrying the gaseous products of the cartridge.

In order that the invention may be more clearly understood one preferred example will now be described with the aid of the accompanying drawings, in which—

Figure 1 is a central sectional elevation, drawn to some extent schematically, of one preferred construction;

Figure 2 is a schematic representation of a general layout of a complete starter mechanism;

Figure 3 is a sectional view in a plane transverse to the axis of the cylinder of the auxiliary engine of a detail of the invention;

Figure 4 is a section similar to Figure 1 showing a modified construction of that portion of the apparatus by which drive is transmitted from the cartridge operated device to the lay shaft, and

Figure 5 is a section on the line 5—5 of Figure 4 looking in the direction of the arrows.

Like reference numerals indicate like parts in the several figures of the drawings.

In accordance with the invention there is employed a single cylinder internal-combustion engine of approximately 6 horse-power, the cylinder of which is indicated at 10. This engine has an over-hung crank 11 on a crankshaft 12 which is mounted at its ends in bearings 13, 14 and 15 carried by the walls of a built-up housing 16 of the apparatus, the crank-case 17 being formed as an extension of this housing and having an end cover 18 in which the bearing 13 is provided.

On the crankshaft 12 which carries a flywheel 19 for the auxiliary engine there is a splined sleeve 20 having two pinions 21 and 22 of different sizes which can be brought alternatively into mesh with co-operating pinions 23 and 24 carried by a lay shaft 25 also contained in the housing 16 and supported therein in bearings 26. Any means, one of which is indicated by a forked lever 27, may be utilised for shifting sleeve 20 to change the gear ratio of the drive between it and the lay shaft 25, this fork being shown as actuated by a rod or cable 28 operating against the action of a return spring 29. A simple change-speed gear is thus provided between the crankshaft and the lay shaft.

The cartridge operated device consists of a cylinder and piston 30 and 31 of which the cylinder 30 is mounted on the housing 16 and the piston is connected to a crank 32 that is rotatable on the layshaft, and is coupled to the crankshaft through a free-wheel device of which the gear 33 constitutes a member of the device that is driven in one direction only by the crank 32 and is in mesh with a corresponding gear tooth 34 formed on the crankshaft 12.

The dotted lines between the crank disc in

which the crank pin 32 is located and the inner recess in gear 33 may be taken as representative of any preferred form of free-wheel device which enables the piston 31 to drive gear 33 in one direction only. Such free-wheel devices, however, are so well known that more than a mere diagrammatic representation is unnecessary.

The lay shaft 25, at that end remote from the auxiliary engine 10, carries a pinion 35 which meshes with an internally toothed wheel 36 carried on a driven shaft 37. The forward end of the latter, that is to say, the end remote from the auxiliary engine 10, is connected by means of a friction clutch 38 with a sleeve 39 which is rotatable on the shaft 37 and is integral with a sun pinion 40 of an epicyclic reduction gear. This pinion meshes with planetary pinions 41 rotatable on a planet carrier 42 which itself is rotatable on sleeve 39 and is integral with another sun pinion 43 of a second epicyclic reduction gear. 20 Planetary pinions 44 co-operating with the sun wheel 43 are rotatable on a second planet carrier 45 which is also mounted for rotation on sleeve 39. The planet pinions 41 and 44 of both epicyclic gears mesh with internally toothed rings 46 and 47 respectively fixed in the housing 16.

The planet carrier 45 has a tubular extension formed with a plurality of spaced inclined ramps 48 and these ramps engage with teeth 49 provided on the inner end of a starter dog 50 which itself comprises a tubular portion 51 within which the friction clutch 38 is located. Initial rotation of the planet carrier 45 produces, by co-operation between the inclined portions of the ramps 48 and teeth 49 lengthwise movement of the starter dog 50 to engage it with a cooperating dog (not shown) on the engine to be started. The ramps 48 terminate in abutments 52 which co-operate with portions of the teeth 49 on the starter dog so as to rotate the latter after it has been moved 40 endwise into engagement with the dog on the engine to be started.

The cylinder 30 is connected by means of a pipe 53 to a cartridge firing chamber diagrammatically indicated at 54 in Figure 2 having for instance an automatic feeding and firing mechanism such, for example, as that described in the specification of prior British Letters Patent No. 513,179 or United States application Serial No. 375,967.

The auxiliary engine is provided with a carburettor 55 preferably of the floatless type and with ignition means of any convenient form which is preferably independent of any external device and may therefore consist of a magneto 56 of the fly-wheel type for instance electrically connected to a spark plug 57 for the cylinder 10.

The auxiliary engine will normally be cold on starting but will quickly heat up and in consequence it is advisable to reduce the richness of the fuel supplied to the engine during the time the auxiliary engine is running from the start. For this purpose a valve 58, Figure 3, for controlling the richness of the fuel supplied to the auxiliary engine is automatically controlled by the engine so that after a given time of running, which may be of the order of four or five seconds, the fuel mixture is automatically weakened. This may occur gradually so as to ensure continued proper running of the auxiliary engine. For this purpose there is employed according to one arrangement as illustrated in Figures 2 and 3, a valve 58 which serves to strangle the air supply to the carburettor 55, or the induction system of the auxiliary engine, and this valve is biased by a spring 59 towards a closed or partly closed

position. The spring 59 operates at one end of a rod 60 which turns with the spindle of valve 58 and on the opposite side of the axis of the spindle this rod is connected by a link 61 to a piston 62 working in a cylinder 63, the interior of which communicates through a passage 64 to the engine crankcase 17. A control valve 65 is inserted in the connection between the passage 64 and the interior of the cylinder 63 and in this connection there is a non-return valve 66. A small bleed passage 67 is provided between cylinder 63 and passage 64.

In operation of this device, on starting the auxiliary engine, crankcase compression is applied to the interior of the cylinder 63 and gradually builds up. In consequence piston 62 is moved to operate the strangler valve 58 against the action of its biasing spring 59 so as gradually to weaken the fuel mixture supplied to the auxiliary engine. The control valve 65 serves to regulate the rapidity with which pressure builds up in cylinder 63 and consequently the rate at which the strangler valve is turned to weaken the mixture for a given engine speed. Valve 65 may, therefore, be adjusted according to the conditions of operation and the characteristics of the auxiliary engine.

A relief valve 68 is provided in the crankcase 17 to be opened when the auxiliary engine stops and to permit gas pressure in cylinder 63 to escape through bleed passage 67 and relief valve 68. Thus, in the event of an unsuccessful attempt to start the auxiliary engine the strangler valve will immediately be returned to a position providing a rich fuel mixture. One relief valve 68 also serves to drain the crankcase under conditions in which the auxiliary engine is of the two-stroke type in which crankcase compression is utilised for the induction system.

For control of the starting apparatus there is preferably employed a single control member diagrammatically indicated at 69 having, for example, a pull knob 70 or, alternatively, an electric switch for putting the starting apparatus into and out of operation. The details of construction and arrangement of the device 69 and its action on the various parts it controls may be modified in many ways, and it suffices for the present description merely to indicate by diagram the operations which it is intended to perform. For instance, the knob 70 is arranged through a connection 71 to close relief valve 68; through a connection 72 to switch on the ignition for the auxiliary engine; through a connection 73 to open a valve 74 controlling fuel supply to the engine; and through a connection 75 to operate the cartridge feeding and firing mechanism. The operations will preferably be performed in the order above stated. Stopping of the auxiliary engine may be effected by releasing the pull knob 70 or by manually returning it to its initial or starting position. As stated above, the control may be either mechanical, electrical, hydraulic or pneumatic provided that the functions performed by the apparatus are those just described.

It will be understood that to commence turning the engine to be started the apparatus according to this invention will function as follows. Firing of a cartridge provides a gas pressure which is supplied to cylinder 30 and this pressure acting on piston 31 turns the lay shaft 25 through a part of a revolution and thus turns the auxiliary engine through the reduction gearing 20 to 24. Assuming the auxiliary engine to have been started, continued rotation of that engine is permitted by

a free-wheel device 33 and further rotation of the lay shaft is continued by the drive from the auxiliary engine and is applied through gear 35, ring gear 36, clutch 38 and the two following epicyclic gears 41 to 41 to the starter dog 50 which, as above stated, will be moved by the initial rotation first to engage the co-operating dog (not illustrated) on the engine to be started and will, therefore, turn that dog and the shaft of the last-named engine. On the starting of the main engine the dog, for the latter overrides the starter dog and causes disengagement between them to take place.

It will be seen that rotation of the auxiliary engine immediately connects the drive through the starter dog to the engine to be started. It is well known that for internal-combustion engines the torque remains substantially constant throughout a wide range of speeds and consequently it is proposed in this apparatus that the auxiliary engine should take up the load of the engine to be started immediately upon the starting of the auxiliary engine.

Alternatively, the auxiliary engine may be permitted to reach an appreciable speed before the load is applied, for which purpose the arrangement illustrated in Figures 4 and 5 may be employed. In this case, as in the previous example, rotary movements imparted to shaft 12 through gear 33 and the shaft 12 drives the change-speed gear, coupling it with the lay shaft 25 through the medium of a centrifugal clutch. The clutch comprises a clutch disc 80 and centrifugal clutch plates 84 which are free to move under centrifugal action to bring surfaces such as 82 into frictional driving engagement with an overhanging flange 83 provided at the periphery of the clutch disc 80. The plates 84 are normally drawn towards one another and to the declutched position by means of tension springs 88 and are guided on and driven by pins 84 extending from the flywheel 19 into slots 85 in the plates. When the speed of the auxiliary engine has attained the desired value the plates 80 will be engaged with flange 83 sufficiently firmly to drive disc 80 and one member 86 of a dog clutch which is formed integrally with the disc. The other member 87 of the dog clutch is integral with the sleeve carrying gears 21 and 22 and any preferred means may be provided to shift sleeve 20 to change the drive speed imparted to the lay shaft 25 through the change speed gearing.

The centrifugal clutch above described may be considered as typical of any preferred form of speed operated clutch by which the auxiliary engine will be allowed to run up to a predetermined speed before taking up the load represented by the turning over of the main engine for starting purposes.

The frictional torque of the engine to be started depends very largely upon temperature conditions and the change-speed gear 20 to 24 is provided so that a gear ratio can be selected according to temperature conditions such that the delivered torque of the auxiliary engine will always be greater than the frictional torque of the engine to be started for the desired range of auxiliary engine speed.

The operation of the change-speed gear may be effected by a remote control which is not shown but which may be situated on the housing of the apparatus itself.

The starting of the main engine releases the load from the auxiliary engine and when this occurs a considerable increase in speed of the auxiliary engine will take place or will tend to take

place. Any preferred means may therefore be provided for operation by the auxiliary engine to switch off the ignition or to operate a throttle for stopping the auxiliary engine and such a control should be arranged to override the manual control 69, 70.

It will be further realised that the invention is not limited to the specific construction of apparatus hereinbefore described. For example, control of the fuel mixture for the auxiliary engine may be operated by centrifugal means driven by the engine itself or by a timing means instead of by the action of piston 62 in the example illustrated.

I claim:

1. Apparatus for starting a main internal-combustion engine comprising, in combination, an auxiliary internal-combustion engine, motion-transmission means for coupling the auxiliary engine to the main engine including a releasable coupling member and a reduction-gear train interposed between the auxiliary engine and the coupling member, a cartridge-operated power device, motion-transmission means operatively connecting the power device with the auxiliary engine and serving to start the latter, a cartridge-firing mechanism, means serving to condition the auxiliary engine for running, and a control member operatively connected to said firing mechanism and to said conditioning means whereby the single control member serves to set the starter apparatus fully into operation, said conditioning means including an ignition switch for the auxiliary engine and means to control the supply of fuel to the auxiliary engine, the ignition switch and fuel control means each having operative connections with said control member.

2. Apparatus for starting a main internal-combustion engine comprising, in combination, an auxiliary internal-combustion engine, motion-transmission means for coupling the auxiliary engine to the main engine including a releasable coupling member and a reduction-gear train interposed between the auxiliary engine and the coupling member, a cartridge-operated power device, motion-transmission means operatively connecting the power device with the auxiliary engine and serving to start the latter, a cartridge-firing mechanism, means serving to condition the auxiliary engine for running, and a control member operatively connected to said firing mechanism and to said conditioning means whereby the single control member serves to set the starter apparatus fully into operation, said conditioning means including an ignition switch, fuel control means, and means for opening and closing a relief valve in the crankcase of the auxiliary engine, each of said ignition switch, fuel control means, and opening and closing means, having operative connection with said control member.

3. Apparatus for starting a main internal-combustion engine comprising, in combination, an auxiliary internal-combustion engine, motion-transmission means for coupling the auxiliary engine to the main engine including a releasable coupling member and a reduction-gear train interposed between the auxiliary engine and the coupling member, a cartridge-operated power device, motion-transmission means operatively connecting the power device with the auxiliary engine and serving to start the latter, a cartridge-firing mechanism, an ignition switch and a fuel-supply control means for the auxiliary engine, a cartridge-firing control member

operatively connected to said mechanism, to said switch to said fuel-supply control means, and to the cartridge-firing mechanism, whereby said control member serves to set the starter apparatus fully into operation.

4. Apparatus for starting a main internal-combustion engine comprising, in combination, an auxiliary internal-combustion engine, motion-transmission means for coupling the auxiliary engine to the main engine including a 10 releasable coupling member and a reduction-gear train interposed between the auxiliary engine and the coupling member, a cartridge-operated power device, motion-transmission means operatively connecting the power device with the auxiliary engine and serving to start the latter, a cartridge-firing mechanism, an ignition switch and a fuel-supply control means for the auxiliary engine, a relief valve in the auxiliary engine crankcase, a cartridge-firing control member operatively connected to said mechanism, to said switch, to said fuel-supply control means, and to said means for opening and closing the relief valve.

5. Apparatus for starting a main internal-combustion engine comprising, in combination, an auxiliary internal-combustion engine, motion-transmission means including a centrifugal clutch for coupling the auxiliary engine to the main engine, said means also including a 25 releasable coupling member and a reduction-gear train interposed between the auxiliary engine and the coupling member, a cartridge-operated power device and a second motion-transmission means operatively connecting the power device with the auxiliary engine and serving to start the latter.

6. Apparatus for starting a main internal-combustion engine comprising, in combination, an auxiliary internal-combustion engine which is additional to the main engine, means for coupling it to the main engine including a reduction gear train, a cartridge-operated device operatively connected with and serving to start the auxiliary engine, cartridge-firing mechanism, means serving to condition the auxiliary engine for running, and a single control-member operatively connected to said firing mechanism and to said auxiliary engine conditioning means, whereby said single control-member serves to set the starter apparatus fully into operation.

7. Apparatus for starting a main internal-combustion engine, comprising, in combination, an auxiliary internal-combustion engine which is additional to the main engine, means coupling it to the main engine including a reduction gear train, and a cartridge-operated device operatively connected with and serving to start the auxiliary engine, said cartridge-operated device comprising a piston and cylinder combined with a crank operated by the said piston, said crank being freely rotatable on a lay-shaft, a freewheel mechanism mounted on said lay-shaft, and gearing connecting said freewheel mechanism with the shaft of the auxiliary engine, said freewheel enabling a partial rotation of the lay-shaft to initiate rotation of the shaft of the auxiliary engine.

8. Apparatus for starting a main internal-combustion engine comprising, in combination, an auxiliary internal-combustion engine which is additional to the main engine, means coupling it to the main engine including a reduction gear train, and a cartridge-operated device operative-

ly connected with and serving to start the auxiliary engine, said cartridge-operated device comprising a piston and cylinder combined with a lay-shaft having a crank thereon with the piston connected to said crank, a freewheel mechanism and gearing coupling the crank to the shaft of the auxiliary engine, and change-speed gearing carried by said lay-shaft and constituting a part of the coupling between the auxiliary engine and the main engine.

9. Apparatus for starting a main internal-combustion engine comprising, in combination, an auxiliary internal-combustion engine which is additional to the main engine, means for connecting it to the main engine including a coupling means a reduction gear train interposed between the auxiliary engine and the coupling means, and a cartridge-operated device operatively connected with and serving to start the auxiliary engine, said cartridge-operated device comprising a piston and cylinder combined with a lay-shaft having a crank freely rotatable thereon and to which the piston is connected, and means including freewheel mechanism coupling the crank to the shaft of the auxiliary engine, change-speed gearing coupling the lay-shaft to the auxiliary engine, and epicyclic gearing coupling the lay-shaft to the coupling means.

10. Apparatus for starting a main internal-combustion engine comprising, in combination, an auxiliary internal-combustion engine which is additional to the main engine, means for connecting it to the main engine including a coupling means, a reduction gear train interposed between the auxiliary engine and the coupling means, and a cartridge-operated device operatively connected with and serving to start the auxiliary engine, said cartridge-operated device comprising a piston and cylinder combined with a lay-shaft having a crank thereon to which the piston is connected, freewheel mechanism coupling the lay-shaft to the auxiliary engine, change-speed gearing also coupling the lay-shaft to the auxiliary engine, epicyclic gearing coupling the lay-shaft to the main engine, and a friction clutch interposed between the output member of the epicyclic gearing and a part of the coupling means through which torque from the auxiliary engine is transmitted to the main engine.

11. Apparatus for starting a main internal-combustion engine, comprising, in combination, an auxiliary internal-combustion engine which is additional to the main engine, means coupling it to the main engine including a reduction gear train, a cartridge-operated device operatively connected with and serving to start the auxiliary engine, a lay-shaft operatively connected to the cartridge-operating device, and means including a freewheel mechanism for coupling the cartridge-operated device to the shaft of the auxiliary engine, change-speed gear coupling the lay-shaft to the shaft of the auxiliary engine, epicyclic gearing coupling the lay-shaft to a coupling member, said coupling member comprising an auxiliary movable toothed clutch member having inclined toothed surfaces to cooperate with corresponding surfaces on a companion clutch member coupled to the shaft of the auxiliary engine through said epicyclic gearing and change-speed gearing, and a friction clutch interposed between the change-speed gearing and the input element of the epicyclic gearing.

HARRY DA COSTA.
